[57] CLAIM

The ornamental design for a children's vehicle, as shown and described.

DESCRIPTION

FIG. 1 is a perspective view of a children's vehicle showing our new design;

FIG. 2 is right side elevational view thereof;

FIG. 3 is a top view thereof;

FIG. 4 is front view thereof;

FIG. 5 is a bottom view thereof;

FIG. 6 is a left side elevational view thereof; and

FIG. 7 is a rear view thereof; and,

FIG. 8 is a perspective view of a modified embodiment of the design shown in FIGS. 1-7.

The broken line showing of the wheels in FIGS. 1-8 is for illustrative purposes only and forms no part of the claimed design.
